DESIGN FOR A GLASS DECANTER OR ARTICLE OF SIMILAR NATURE

Charles L. Fordyce, New York, N. Y., assignor to
Pitman-Dreitzer & Co., Inc., New York, N. Y.,
a corporation of New York

Application February 16, 1945, Serial No. 118,002

Term of patent 14 years

(Cl. D36—2)

To all whom it may concern:

Be it known that I, Charles L. Fordyce, a citizen of the United States of America and a resident of New York, in the county of New York and State of New York, have invented a new, original, and ornamental Design for a Glass Decanter or Article of Similar Nature, of which the following is the specification, reference being had to the accompanying drawing, forming a part thereof.

Figure 1 is an elevational view of a glass decanter showing my design.

Figure 2 is a fragmentary view taken at right angles to Figure 1 showing a section of the neck and an edge view of the stopper.

I claim:

The ornamental design for a glass decanter or article of similar nature, substantially as shown.

CHARLES L. FORDYCE.
